UNITED STATES PATENT OFFICE.

HENRY STERNBERGER, OF CINCINNATI, OHIO.

HANDKERCHIEF.

No. 826,126.

Specification of Letters Patent.

Patented July 17, 1906.

Application filed September 17, 1904. Serial No. 224,839.

To all whom it may concern:

Be it known that I, HENRY STERNBERGER, a citizen of the United States of America, and a resident of Cincinnati, in the county of Hamilton and State of Ohio, have invented certain new and useful Improvements in Handkerchiefs, of which the following is a specification.

This invention relates to improvements in handkerchiefs or, more particularly speaking, to ladies' dress-handkerchiefs; and the object of the invention is to provide a handkerchief with a simple, economical, and unnoticeable means for holding or containing face-powder adapted to ready application and use and to avoid the objectionable feature of carrying and using a separate cloth, chamois, or puff, as heretofore the practice in places away from the privacy of the dressing-apartment 20 at home.

The invention consists in a handkerchief, one side of which is provided with a surface of velveteen or other like nap or pile adapted to receive and retain a quantity of face-powder for ready and convenient application, all as will be hereinafter fully set forth.

In the accompanying drawings, which serve to illustrate my invention, Figure 1 is a plan view of a handkerchief, showing the side thereof that embodies my invention; and Fig. 2 is a transverse section taken on the dotted line $x x$ of Fig. 1.

In the views, 1 indicates the body portion of the handkerchief, composed of linen, silk, or any of the customary materials or fabrics, and 2 indicates an ordinary hemstitched border on said body portion, the latter having therein an insertion 3 of lace or the like.

The handkerchief thus far is as usual and 40 not out of the ordinary at all, and it may have other borders or the insertion omitted; but it being intended especially as a lady's dress-handkerchief it should have more or less embellishment.

45 4 indicates a surface for containing and applying face-powder or other similar preparation. This surface 4 is preferably of velveteen suitably attached to or woven integral with one side of the body portion 1, covering 50 the internal or middle area inside the insertion 3, as shown in both the views of the drawings. The surface 4 may comprise a separate piece of velveteen stitched or otherwise secured along its four edges to the body portion 1 adjoining the insertion 3, or the velveteen nap or pile may be interwoven with the material of the body portion of the handkerchief so as to project slightly or minutely from its surface and form a holding or absorbing surface for the face-powder, and a 55 soft, smooth, and desirable means for applying the latter in use. Instead of velveteen, the surface 4 may be of velvet, plush, or other like pile; but I prefer velveteen for the reason that it holds the powder well, washes well, 60 and does not shrink in said wash, all of which are important features. Surface 4 forms an auxiliary face-powder holding and applying one for handkerchiefs, and the side it is applied to then becomes the back of the apparel 70 practically, the same being unnoticeable to view when carrying it by the usual folding thereof or taking it by the center with the other or usual face exposed outward.

To all appearances my handkerchief is 75 nothing but an ordinary one, as the face-powder-containing side is not exposed to view, and even if it were, by accident or otherwise, the pile material used is of the same hue as the handkerchief fabric and is not noticeable, as hereinbefore stated.

The surface 4 does not in any wise interfere with or affect the regular use of the handkerchief, and its application thereto adds but little expense in manufacture. 85

I claim—

A lady's combined dress-handkerchief and powder-cloth, comprised in its entirety of a body portion, a section of velveteen of the same area as said body stitched along all four 90 of its sides to said body so as to have its edges lie flush with the edges of said body, said velveteen constituting a face-powder holding and applying surface, a border surrounding said body and spaced therefrom, and insertion connecting said border to said body portion. 95

Signed at Cincinnati, Ohio, this 7th day of September, 1904.

HENRY STERNBERGER.
